UNITED STATES PATENT OFFICE.

SPENCER E. CARR, OF PHILADELPHIA, PENNSYLVANIA.

BURGLAR-ALARM.

SPECIFICATION forming part of Letters Patent No. 339,854, dated April 13, 1886.

Application filed February 8, 1886. Serial No. 191,208. (No model.)

To all whom it may concern:

Be it known that I, SPENCER E. CARR, a citizen of the United States, residing in Philadelphia, Pennsylvania, have invented certain 5 Improvements in Burglar-Alarms, of which the following is a specification.

My invention relates to that class of burglar-alarms in which a drop-block carrying a cartridge and firing-pin is supported adjacent to a door, so that when the door is opened the block will be allowed to fall and the cartridge exploded.

My improvements comprise a combined thumb screw and pin for supporting the drop-block and the method of constructing said drop-block and combining the firing-pin therewith, so that the manufacture and fitting together of the parts is simplified, and the cost of the device reduced to a minimum.

20 In the accompanying drawings, Figure 1 is a perspective view, partly in section, showing the application of my improved burglar-alarm to a door and door-frame; Fig. 2, a sectional view, partly in elevation, and on a larger scale than Fig. 1; Fig. 3, a perspective view of the combined thumb-screw and supporting-pin forming one of the features of the invention; Fig. 4, a perspective view of the firing-pin forming part of the device; Fig. 5, a sectional 25 plan on the line 1 2, Fig. 2; and Fig. 6, a sectional view showing a modification of my invention.

A represents part of a door, and B part of the door-frame, into which, at a point just 35 above the upper edge of the door, is screwed a threaded pin, *a*, having an enlarged and flattened head, *b*, so that it forms a thumb screw which can be readily manipulated. From the head *b* projects a pin, *d*, which is adapted to 40 an eye, *e*, at the upper end of a block, D, the latter having a transverse recess, *f*, with which communicates a vertical opening, *g*, intended for the reception of a cartridge, *x*, as shown in Fig. 2, this opening being enlarged in diameter at the lower end for the reception of a 45 firing-pin, *F*, which is free to move vertically within the opening to an extent limited by a transverse pin, *h*, carried by the block D, the inner end of said pin projecting into a groove, *i*, in the firing-pin, which groove is of some- 50 what greater width than the diameter of the

pin. The firing-pin *F* has an enlarged head, *m*, at the bottom, and when, on the opening of the door A, the block D is thrust from the pin *d* and allowed to fall, the head of the firing-pin strikes the floor and the cartridge is thereby brought into forcible contact with and exploded by a teat, *n*, on the firing-pin.

In order to permit the withdrawal of the firing-pin when it is desired to remove the shell 55 of an exploded cartridge and the insertion of a new cartridge in its place, the flange *s* of the firing-pin above the groove *i* has a notch, *t*, at one side, for the passage of the pin *h*, so that when it is desired to withdraw the pin *F* the latter is turned until the notch is in line with 60 said pin *h*, a like adjustment of the pin being effected when the latter is reintroduced, and the pin being turned when the flange *s* has passed the pin *h*, so that the latter will engage 65 with the flange and retain the pin *F* in place.

The grooved portion of the pin *F* is preferably provided with a stop-lug, *w*, which, by contact with the pin *h*, serves to limit the turning movement of the pin *F* when the latter has 70 reached the position in which it should be allowed to remain—that is to say, the position in which the notch *t* of the flange *s* is farthest removed from the retaining-pin *h*.

By constructing the block and firing-pin in 75 the manner set forth, I am enabled to simplify the device and reduce the cost of the same to a minimum, as no threading or other expensive machine-fitting of the parts is required. The pin *h* may be so fitted to the block that 80 it can be moved laterally, in which case the notched flange *s* of the firing-pin will be unnecessary, the inner end of the pin *h* being projected into the recess *i* of the firing-pin after the latter has been inserted into the block. 85

If desired, the exploding device may be in the form of a cap, embracing the lower portion of the block D and having a pin, *h*, supported by a flange, *s*, on the block, said flange having a notch, *t*, for the passage of the pin, 90 as shown in Fig. 6.

I claim as my invention—

1. The within-described holder for a detonating burglar-alarm, said holder consisting of a screw-pin, *a*, having a flattened head, *b*, with a projecting pin *d*, all substantially as specified. 100
2. The combination of the block D, having

an opening for the reception of a cartridge, an exploding device, an annular flange formed on one of said parts and having a notch at one side and a retaining-pin on the other part for engagement with said notched annular flange, all substantially as specified.

3. The combination of the block D, having an opening for the reception of a cartridge, the internally-projecting pin *h*, and a firing-pin 10 adapted to the opening in the block and having a recess, *i*, for the reception of the retaining-pin, said recess being of greater width than the diameter of the pin, all substantially as specified.

4. The combination of the block D, having 15 an opening for the reception of a cartridge, the internally-projecting retaining-pin, and a firing-pin having a notched flange, *s*, and recess *i*, for the reception of the retaining-pin, all substantially as specified. 20

In testimony whereof I have signed my name to this specification in the presence of two subscribing witnesses.

SPENCER E. CARR.
